COIN BANK

Carl G. Bergman, Highland Park, Mich.

Application July 2, 1952, Serial No. 20,451

Term of patent 7 years

(Cl. D34—11)

To all whom it may concern:

Be it known that I, Carl G. Bergman, a citizen of the United States of America, residing at Highland Park, in the county of Wayne and State of Michigan, have invented a new, original, and ornamental Design for a Coin Bank, of which the following is a specification, reference being had to the accompanying drawing, forming part thereof.

Figs. 1, 2, 3, and 4 are front, rear, top and side views respectively of a coin bank, showing my new design.

The rectangular central front portion of Fig. 1 is lined to indicate a transparent plate.

I claim:

The ornamental design for a coin bank, as shown and described.

CARL G. BERGMAN.
